E. A. Ellsworth

United States Patent Office.

EDWARD A. ELLSWORTH, OF WASHINGTON, DISTRICT OF COLUMBIA.

Design No. 4,442, dated October 25, 1870.

DESIGN FOR GROUP OF TOOLS, MACHINERY, &c.

The Schedule referred to in these Letters Patent and making part of the same.

To all whom it may concern:

Be it known that I, EDWARD A. ELLSWORTH, of Washington, in the county of Washington and District of Columbia, have invented and produced a new and original Design for Ornamenting Envelopes, Cards, Letter-Heads, Circulars, &c., of which the following is a specification.

The nature of my design is fully represented in the accompanying drawing, to which reference is made.

Claim.

I claim as my invention—
The design for ornamenting envelopes, cards, letter-heads, circulars, &c., as shown.

E. A. ELLSWORTH.
